UNITED STATES PATENT OFFICE.

ALBERT C. TOLIVER, OF GLENROCK, WYOMING, ASSIGNOR OF ONE-HALF
TO J. F. PATTERSON, OF GLENROCK, WYOMING.

DRAFT-PRODUCER AND SPARK-ARRESTER.

SPECIFICATION forming part of Letters Patent No. 768,782, dated August 30, 1904.

Application filed July 22, 1903. Serial No. 166,640. (No model.)

To all whom it may concern:

Be it known that I, ALBERT C. TOLIVER, a citizen of the United States, residing at Glenrock, in the county of Converse and State of Wyoming, have invented a certain new and useful Draft-Producer and Spark-Arrester, of which the following is a specification.

The invention relates to a draft-producer and spark-arrester; and it has for its object 10 to provide a simple and comparatively inexpensive device adapted to be readily applied to locomotives and capable of producing a steady draft through the smoke-stack and of simultaneously arresting and extinguishing 15 the sparks.

With these and other objects in view the invention consists in the construction and arrangement of parts hereinafter described and claimed, and illustrated in the accompanying 20 drawings.

In the drawings forming part of this specification, and in which like letters of reference designate corresponding parts, Figure 1 is a vertical sectional view of a combined draft- 25 producer and spark-arrester constructed in accordance with this invention and shown applied to a locomotive-boiler. Fig. 2 is a horizontal sectional view. Fig. 3 is a detail perspective view of the rotary fan.

Referring to the drawings, F designates an exhaust-steam pipe arranged vertically in and extending upward from the bottom of the smoke-box X of a locomotive-boiler and provided near its upper end with an interiorly- 30 arranged spider E', forming a support for an annular series of antifriction-balls D', on which is arranged an annular shoulder or bearing of a vertical shaft A. The vertical shaft A, which consists of a tube, is supported at its 35 lower portion by antifriction-balls D', and it is provided at its upper end with a ball-cup, receiving an annular series of antifriction-balls D, which bear against a top spider E, the upper balls D being interposed between 40 the cup and the central portion of the spider, which is provided with an opening for the upper end of the hollow shaft. The upper spider is secured within the top of the stack,

as shown. The hollow shaft is provided opposite the antifriction-balls with perforations, 50 and the said balls are lubricated by the oil carried upward by the exhaust-steam.

Mounted upon the shaft is a rotary fan consisting of a cylindrical casing having a cap O at its lower end to fit over the upper end of 55 the exhaust-pipe F. The fan is provided with a series of spirally-arranged hollow blades G, communicating at their lower ends with the cap and forming spiral passages for the exhaust-steam, whereby the fan will be rotated 60 when the steam passes upward through such spiral passages. The spiral blades, which extend upward around the fan from the cap O to the top of the tubular casing, are adapted when the fan rotates to create a draft in the 65 smoke-stack I. This steady draft not only insures the proper burning of the fuel, but prevents sudden and jerky puffs which often dislodge the coal from the grate and result in choking the boiler-tubes. The spiral blades 70 may be of any desired size and number to adapt the device to the character of the fuel employed.

Within the smoke-stack I is arranged a cylindrical jacket H, which surrounds the fan 75 and which prevents the heat from warping or otherwise injuring the smoke-stack. The upper portion of the jacket is provided with perforations K, and the sparks are thrown outward by centrifugal force and are forced 80 through the perforations of the jacket, thereby extinguishing the sparks and causing the cinders to collect or to be thrown into the diamond-shaped smoke-stack. This prevents 85 the damage which often results from the live sparks emitted by a locomotive.

What I claim is—

1. In a device of the class described, the combination with a smoke-stack of a jacket arranged therein and having apertures and a rotary fan operating in the jacket and adapted to throw the sparks against the same, substantially as described.
2. In a device of the class described, the combination with a smoke-stack, of a rotary fan provided with interiorly-arranged spiral

passages and means for conducting exhaust-steam to the passages, substantially as described.

3. A device of the class described, comprising a rotary fan designed to be mounted in a smoke-stack, and provided with hollow spiral blades having interiorly-arranged spiral passages and means for conducting exhaust-steam to the blades whereby the fan will be rotated by such steam, substantially as described.

4. In a device of the class described the combination with an exhaust-pipe of a fan having a cap fitting over the exhaust-pipe, said fan being provided with hollow spiral

blades communicating with the exhaust-pipe, 15 substantially as described.

5. In a device of the class described, the combination with a stack, and an exhaust-pipe, of upper and lower spiders, a hollow shaft journaled in the spiders ball-bearings arranged 20 at the said spiders, and a rotary fan mounted on the shaft and provided with hollow spiral blades communicating with the exhaust-pipe.

ALBERT C. TOLIVER.
